UNITED STATES PATENT OFFICE.

ISIDOR KITSEE, OF PHILADELPHIA, PENNSYLVANIA.

SIMULTANEOUS TRANSMISSION OF TELEGRAPHIC AND TELEPHONIC IMPULSES.

No. 861,125.

Specification of Letters Patent.

Patented July 23, 1907.

Application filed September 22, 1906. Serial No. 335,780.

To all whom it may concern:

Be it known that I, Isidor Kitsee, a citizen of the United States, residing at Philadelphia, in the county of Philadelphia and State of Pennsylvania, have invented certain new and useful Improvements in Simultaneous Transmission of Telegraphic and Telephonic Impulses, of which the following is a specification.

My invention relates to an improvement in the simultaneous transmission of telegraphic and telephonic impulses. Its object is, to decrease or entirely eliminate the influence of telegraphic impulses on telephonic receivers.

When telegraphing is done with the aid of a straight current, it is comparatively easy to lessen the influence of a telegraphic impulse on the telephonic receiver, for the reason that a path may be established for the telephonic impulses, opaque or nearly so to the impulses due to the make and break of a straight or direct current. For such purpose different arrangements have been devised and are more or less successful. But when the telegraphic impulses are due to induced currents, that is, when the secondary impulses of an inductorium are sent over a line, the same are retarded by the impedance coils just as well as the telephonic impulses, and static means—such as condensers—are just as transparent to the flow of such impulses as to the flow of telephonic impulses. Such arrangements, therefore, as shunting the telephonic receiver with condensers, or trying to side-track, so to speak, the telegraphic induced impulses with the aid of coils opaque to telephonic impulses is out of the question.

In my endeavor to telegraph with induced impulses,—impulses generated in the secondary of an inductorium through the make and break of a circuit including the primary of said inductorium,—and to simultaneously transmit over one and the same line telephonic impulses, I have tried above arrangements but with no avail. All branch circuits opaque to the induced telegraphic impulses were found to be opaque to the telephonic impulses and vice versa. All branch circuits transparent to the telephonic impulses were also found to be transparent to the induced telegraphic impulses. I then had recourse to the shunting of the battery connected to the primary coil with the aid of condensers, but found no relief; so also did I try the shunting of the key with the aid of condensers with the same negative result. I then had recourse to the shunting of the secondary coil inserted in the line with the aid of condensers and found entire relief when the condenser represented a capacity of about five microfarads. The line I made these experiments on was somewhat more than forty four miles in length, and I tried these experiments by, first producing an all-

metallic line; secondly, producing a one-conductor line grounded; and thirdly, producing, what I call, a composite line, that is, a line consisting of two conductors insulated from each other but in inductive relation to each other, one conductor grounded with one terminal, the other terminal being free, and the second conductor grounded with the opposite terminal, leaving its other terminal free.

In my tests which gave satisfactory results, I used as a telegraphic transmitting device an inductorium, an ordinary Morse transmitting key and a source of current equal to about three volts. The secondary of the inductorium was connected in series as to the line and was provided with means to vary its resistance from six ohms to somewhat over two hundred ohms. The primary had a resistance of about three-fourths of an ohm. The receiving device consisted of a polarized relay with a combined resistance of the coils equal to about fifteen hundred ohms. The coils were wound with No. 36 silk covered wire. The telephonic transmitter consisted of the usual desk phone, an inductorium, the primary with about three-fourths of an ohm and the secondary provided with means to vary its resistance from six ohms to two hundred ohms. The force used was about one volt more than the force used with the telegraphic transmitting device. The telephonic receiver was a common ear-phone. The line, as said above, had a lineal length of nearly forty five miles. The best results were obtained when the different coils of the secondary of the telegraphic transmitter were connected in multiple, so as to give a combined resistance of twelve ohms.

It has to be stated here, that the telephonic receiver was not connected directly to the line, but with the interposition of an inductorium, the secondary of which was connected to the line and the primary therefor to the receiver proper. The secondary of this inductorium presented a resistance of about six ohms.

Referring to the drawing, Figures 1, 2 and 3 are diagrammatic views of different circuits including telegraphic and telephonic devices and embodying my invention. Fig. 1 is a one-conductor line grounded on both ends; Fig. 2 is a composite line consisting of two conductors, each grounded with one terminal; Fig. 3 is a composite line comprising two composite conductors, each consisting of two conductors in inductive relation to each other; all four conductors forming two open circuits.

In Fig. 1, 1 is the line of transmission; 20 are the grounds for same; 60 is the telegraphic transmitting device as an entirety; of this 10 is the inductorium used as a telegraphic transmitter. Of this inductorium, 11 is the secondary connected in the line and provided with means 12 to vary its inductive value. 13 is the

condenser shunting the secondary; 14 is the primary; 15 the key; and 16 the source of current, here shown as two batteries. 30 is the telephonic transmitting device as an entirety, comprising—as usual—the inductorium 5 31, the micro-phonic transmitter 32 and source of current 33. 40 is a telegraphic receiving device, here shown as a polarized relay; 50 is the telephonic receiving device, as an entirety, comprising the secondary 51, the primary 52 of an inductorium and the ear-phone 53.

10 In Fig. 2, the line of transmission consists of the two conductors 1 and 2 insulated from each other, but in inductive relation to each other. These conductors are grounded at 20.

In Fig. 3, the line comprises two conducting pairs, 15 one conducting pair comprising the conductors 1 and 2, and the other conducting pair comprising the conductors 3 and 4.

I have shown and described herein subject-matter not claimed, but claimed in my co-pending application 20 Serial No. 338,415, filed October 11, 1906.

Having now described my invention, what I claim as new and desire to secure by Letters Patent is:—

1. In a system of electric signaling over a conductor or circuit, the combination with a conductor or circuit, of 25 means for generating a sharp current impulse, and a storage device of relatively great storage capacity subjected to said impulse, whereby the current flowing over the conductor or circuit assumes the form of an impulse of relatively great duration.

30 2. In a system of electric signaling over a conductor or

circuit, the combination with a conductor or circuit, of means for producing a sharp electrical impulse, and a condenser of relatively great capacity subjected to said impulse, whereby the current flowing over the conductor or circuit assumes the form of an impulse of relatively great 35 duration.

3. In a system of electric signaling over a conductor or circuit, the combination with a conductor or circuit, of a secondary of a transformer, means for generating in said transformer secondary a sharp impulse, and a condenser 40 of relatively high capacity associated with said transformer secondary and said conductor or circuit, whereby the current flowing over said conductor or circuit assumes the form of an impulse of relatively great duration.

4. In a system of electric signaling over a conductor or 45 circuit, the combination with a conductor or circuit, of means for producing a sharp electrical impulse, a condenser of relatively great capacity, and means for impressing said impulse simultaneously upon said circuit or conductor and said condenser, whereby the current flowing 50 over said circuit or conductor assumes the form of an impulse of relatively great duration.

5. In a signaling system, a composite line conductor comprising conductively independent conductors twisted together, and an associated transmitter comprising means 55 for generating a sharp electrical impulse, and a condenser of relatively great capacity subjected to said impulse, whereby the current flowing over the line assumes the form of an impulse of relatively great duration.

In testimony whereof I affix my signature in presence of 60 two witnesses.

ISIDOR KITSEE.
